UNITED STATES PATENT OFFICE

JOSEPH H. GWYNNE, OF WARREN, OHIO

BATCHER

Application filed October 10, 1928. Serial No. 311,672.

The present invention relates to batchers such as are employed for discharging predetermined batches or amounts of sand, gravel or similar material, and the invention aims to provide a novel and improved device of that kind.

Another object of the invention is the provision of a batcher which may be applied to the side wall of a silo or other container for sand, gravel or similar material, to enable measured quantities of the material to be delivered.

The invention has among its other objects to provide a batcher having a novel adjustable measuring chamber, novel means for controlling the flow and discharge of the material, and novel operating means therefor.

With the foregoing and other objects in view, which will be apparent as the description proceeds, the invention resides in the construction and arrangement of parts as hereinafter described and claimed, it being understood that changes can be made within the scope of what is claimed, without departing from the spirit of the invention.

The invention is illustrated in the accompanying drawings, wherein—

Figure 1 is a vertical median section of the improved batcher, taken on the line 1—1 of Fig. 2.

Fig. 2 is a plan view looking in the direction of the arrow 2 in Fig. 1, portions being broken away and shown in section.

Fig. 3 is a cross section on the line 3—3 of Fig. 1.

Fig. 4 is a sectional detail of the operative connection between the rock shafts connecting the gates.

Fig. 5 is an elevation of the cam segment shown in Fig. 4.

The batcher has an inclined spout 1 extending outwardly and downwardly from a substantially vertical plate 2 that is part of a structural metal frame 3 which is secured to the wall of a silo, bin or other container for holding sand, gravel or similar material, in order that the material may flow downwardly and outwardly through the spout 1 into the batcher.

The batcher has a measuring chamber comprising the bottom 4 and sides 5. The bottom 4 is inclined, and the spout 1 enters the upper end portion of the measuring chamber. The side walls 5 have a lower end wall 6 between them, and the lower end portions of the bottom 4 and walls 5 and 6 are formed with a hopper-shaped discharge portion 7 having the opening or outlet 8 to deliver the material into a truck or other receiver.

The top of the measuring chamber includes a fixed upper plate 9 to which partitions 10 are connected, said partitions converging upwardly from the side walls 5 and having the portions 11 at the opposite sides of the spout 1. The plate 9 has an outturned flange 12 at its upper edge adjacent to but spaced from the lower edge of the top of the spout 1, as seen in Fig. 1.

A cut-off gate 13 moves across the lower end of the spout 1 to cut off the flow of material through the spout into the measuring chamber. This gate comprises the side plates or segments 14 and a curved plate 15 secured thereon and curved about the axis of the shafts or rods 16 on which the side plates 14 are mounted for turning movement. Said rods 16 are supported by the side walls 5 of the measuring chamber and the side walls 8 of the spout 1.

In order to oscillate the gate 13, a gear segment 17 is mounted on one of the rods 16 and is secured to one side of the gate 13, as seen in Fig. 4, and the segment 17 meshes with a pinion 18 on a transverse shaft 19 journaled on the frame 3. A sprocket wheel 20 is secured on one end of the shaft 19 and a chain 21 passes around said sprocket wheel in order that the chain may be conveniently pulled at 90, a point lower down, for either opening or closing the gate 17.

The lower end of the spout 1 is rounded, as at 22, around the axis of rotation of the gate 13, so that said gate may move close to the end of the spout.

There is a dead space below the spout into which the lower edge of the plate 15 moves, when the gate 13 is closed, thereby permitting the gate to close without being obstructed.

The lower edge of the gate may thus move through the material and under the spout 1 without clogging. The plate 15 of the gate moves between the top of the spout and the plate 9.

The measuring chamber has an adjustable lower end wall 23 movable between the side walls 5 on the bottom 4, and a lower top plate 24 is secured to the end wall 23. The end wall 23 has wings 25 slideable along the side walls 5 and connected by a brace or strut 25a, and oblique portions 26 extend between the wings 25 and end wall 23 and correspond to the side walls of the hopper portion 7 to permit the end wall 23 to be adjusted downwardly to the limit. The end wall 23 may thus be moved down into the hopper portion 7, and when moved upwardly to reduce the size of the measuring chamber, the wings 25 and web portions 26 prevent leakage of the material between the walls 23 and 5.

The top plate 24 has downturned portions 27 at the outer sides of the walls 5 and carries roller carriages 28 movable along outstanding flanges or rails 29 secured to the walls 5, thereby mounting the plate 24 and end wall 23 for free movement.

An intermediate top plate 30 is disposed in overlapping relation with the top plates 9 and 24, as seen in Fig. 1, and has downturned portions 31 at the outer sides of the walls 5 and carries roller carriages 32 movable along the outstanding flanges or rails 33 secured to the side walls 5.

The portions 31, carriages 32 and rails 33 are located between the walls 5 and portions 27 above the rails 29, as seen in Fig. 3, to avoid interference between the mountings of the plates 24 and 30.

Outstanding stops 34 are carried by the walls 5 for the contact of the lower ends of the portions 31, as seen in Fig. 1, to limit the downward movement of the plate 30. The plate 30 closes the space between the plates 9 and 24, and when the wall 23 is moved upwardly it will contact with the plate 30 and move the plate 30 upwardly with the wall 23 over the plate 9. When the plate 24 and end wall 23 are moved downwardly the plate 30 will move downwardly with them, until it is stopped by the stops 34.

The measuring chamber thus has an extensible top composed of the plates 9, 24 and 30.

The end wall 23 is adjusted by means of racks 35 secured on the plate 24 and meshing with pinions 36 secured on a transverse shaft 37 journaled on the frame 3 adjacent to the shaft 19, and the shaft 37 may be rotated by any suitable means (not shown) and locked in any position so as to hold the end wall 23 in the desired adjustment for a corresponding capacity of the measuring chamber.

The end wall 23 has an opening 38, and a discharge gate 39 is hinged, as at 40, to the

wall 23 to swing to and from the opening 38.

The gate 39 has an outstanding arm 41 on which a weight 42 is screw-threaded or otherwise adjustably mounted, so that the weight will swing the gate 39 downwardly and upwardly against the wall 23 across the opening 38.

In order to control the gate 39 toggle links 43 are pivotally connected with the gate 39 and with toggle links 44 that are pivoted to brackets 45 carried by the end wall 23, and the links 44 are connected by a yoke 46 so that the two pairs of toggle links operate simultaneously. The links 43, 44 break upwardly when the gate 39 swings open, as seen in dotted lines in Fig. 1, and move downwardly toward a straightened-out position when the gate 39 is closed, as seen in full lines in Fig. 1.

A link 47 connects one of the toggle links 44 with an arm 48 on a sleeve 49 that is feathered or splined on a rock shaft 50 which has its lower end journaled in a bearing 51 carried by the wall 6 and which has its upper end journaled in a bearing 52 mounted on the frame 3 near the spout 1. The sleeve 49 is slideable on the shaft 50 when the wall 23 is adjusted, and the rocking movement of the shaft 50 will swing the gate 39 open and closed.

The movement of the cut-off and discharge gates is synchronized so that they open and close alternately. For this purpose a sleeve 53 is secured on the shaft 50 adjacent to the bearing 52 and carries a roller 54 working in a groove 55 in a cam segment 56 that is secured between the gear segment 17 and corresponding side plate 15 of the gate 13, as seen in Fig. 4. The groove 55 has an oblique portion 57 near one end to swing the sleeve 53 and turn the shaft 50. Thus, when the cut-off gate 13 is being closed and approaches its closed position the portion 57 of the groove 55 engaging the roller 54 will turn the shaft 50 so as to raise the arm 48, and thereby through the toggle links 43, 44 open the discharge gate 39. Conversely, when the cut-off gate starts to open, the oblique portion 57 of the groove 55 will turn the sleeve 53 and shaft 50 to swing the gate 39 closed before the gate 13 has opened sufficiently to permit the material to flow into the measuring chamber. The discharge gate is thus opened during the final closing movement of the cut-off gate, and is closed during the initial opening movement of the cut-off gate.

The operation of the batcher is simple, and will no doubt be understood from the foregoing, but briefly described is as follows: The end wall 23 is adjusted so that the measuring chamber is of a desired capacity in order to discharge a predetermined batch or quantity of material. When the cut-off gate 13 is opened, the discharge gate 39 is closed during the initial opening movement thereof, and

the material will flow through the spout 1 into the measuring chamber. Then, by closing the cut-off gate 13, the discharge gate is opened during the final movement of the gate 13, thereby permitting the material to discharge from the measuring chamber through the hopper portion 7 and outlet 8.

The cut-off gate 13 does not have a tight fit with the spout 1, but to the contrary there is a clearance between said spout and gate, to permit the gate to move freely. When the gate is closed it provides a pocket under the spout 1 to receive the material and to prevent same from passing down into the measuring chamber until the gate 13 is again opened. The gate 13 may thus swing open and closed freely, and will not be clogged by pebbles, gravel, or the like.

Having thus described the invention, what is claimed as new is:—

1. A batcher comprising a measuring chamber having an inclined bottom, side walls, a lower end wall adjustable between said side walls and an extensible top, said top including overlapping plates, some of which are guided for sliding movement from said side walls, one of said plates being movable with said end wall, said end wall having a discharge gate, and means controlling the flow of material into said chamber.

2. A batcher comprising a measuring chamber having an outlet at its lower end, and an inlet at its upper portion, a cut-off gate for controlling the inlet of material to the measuring chamber, an adjustable lower end wall for the chamber, a discharge gate carried by said end wall and movable therewith, a rock shaft journaled beside said measuring chamber, connections from said rock shaft to the discharge gate including a slidale member on the rock shaft secured to rotate therewith, and means movable with the cut-off gate for rotating said rock shaft on the final closing movement of the cut-off gate and during the initial opening movement of said cut-off gate.

3. A batcher comprising a measuring chamber, a cut-off gate for governing the supply of material to the chamber, a movable lower end wall for the chamber, a discharge gate carried by said lower end wall and movable therewith, a rock shaft journaled beside said chamber, connections between said discharge gate and rock shaft for opening and closing the discharge gate on rotary movement of the rock shaft, said connections including a member on the rock shaft secured to rotate therewith but having free sliding movement with the end wall, and cam means between said rock shaft and the cut-off gate for rocking the rock shaft on final closing movement of the cut-off gate and on initial opening movement of said cut-off gate.

4. A batcher comprising a measuring

chamber, a movable cut-off gate for controlling the supply of material to the chamber, a movable lower end wall for the chamber, a discharge gate carried by said end wall, a rock shaft journaled beside said chamber, connections between said rock shaft and discharge gate including a member fixed to rotate on the rock shaft but slidale thereon with said end wall, a cam member movable with said cut-off gate and having a groove therein with an end oblique portion, and a projection on said rock shaft for traveling in said cam groove whereby to rotate the rock shaft on the final closing and initial opening movement of the cut-off gate.

5. An improved batcher comprising a measuring chamber having a fixed lower discharge opening, a movable end wall within said chamber for regulating the capacity thereof, a discharge gate carried by said movable end wall, a cut-off gate for regulating the supply of material to the chamber, and means located wholly without the chamber operated by said cut-off gate and having a part moving with said adjustable end wall for timing the opening of the discharge gate to occur on the final closing movement of the cut-off gate and the closing of the discharge gate on the initial opening movement of the cut-off gate.

6. A batcher comprising a measuring chamber having a discharge opening at its lower end, a cut-off gate for regulating the inlet of material to the chamber, a movable lower end wall contained wholly within the sides and bottom portion of the measuring chamber and having an upper wall portion thereon, a fixed upper wall portion for the container, an intermediate upper wall portion movable between the first mentioned upper wall portions and disposed in the path of the lower end wall, and a discharge gate carried by the lower end wall.

7. A batcher comprising a measuring chamber having an upper inlet, an enclosed hopper communicating with the lower end of said chamber and having a downwardly directed discharge opening, a movable lower end wall contained wholly within the sides and bottom of the chamber, a discharge gate carried by said lower end wall and opening into the hopper, connections contained within said hopper for operating said discharge gate, and a cut-off gate for controlling the inlet of material to the chamber coupled to open and close alternately with said discharge gate.

8. A batcher comprising a substantially vertical plate, a spout extending downwardly at an angle from said plate, the bottom of the spout forming an acute angle with said plate and providing a dead space between them, a measuring chamber extending from said plate and into which said spout discharges, and an arcuate cut-off gate mount-

ed for turning movement to move down-
wardly across the lower end of said spout and
to bring its leading edge into said dead space

9. A batcher comprising a measuring
chamber having an inclined bottom, side
walls, a lower end wall adjustable between
said side walls and an extensible top adjust-
able with said end wall, a movable cut-off gate
for controlling the supply of material into
10 said chamber, a discharge gate carried by said
end wall, and an operative connection be-
tween said gates located exteriorly of said
chamber.

In testimony whereof I hereunto affix my
15 signature.

JOSEPH H. GWYNNE.
